M. RAYMOND

GARMENT HANGER

1,970,943

Filed Jan. 11, 1932

MORRIS RAYMOND.

By Clarence A. O'Brien
Attorney

UNITED STATES PATENT OFFICE

1,970,943

GARMENT HANGER

Morris Raymond, Brooklyn, N. Y.

Application January 11, 1932, Serial No. 585,999

6 Claims. (Cl. 223—64)

This invention relates to improvements in garment hangers.

One of the features of the invention resides in a hanger which may be converted from a coat hanger to a hat hanger, and vice versa, depending upon the type of garment to be hung.

Another feature of the invention is to provide a hanger of the above kind which may be used in the home and is equally adaptable for use in automobiles when it is desired to hang the hat or coat of the occupants thereof when touring to maintain the same in a hung position against creasing.

A further object is the provision of a garment hanger embodying a pair of pivoted arms which may be swung and locked either in an opposed outwardly extending position to form a coat hanger, or which may be moved and locked in a position wherein they constitute coacting jaws for receiving and holding the crown of a hat to be supported.

A still further object is to provide a combination hanger having the above features of construction, which is simple of construction, inexpensive of manufacture, and easy and quick to operate during the changing of the same from a coat hanger to a hat hanger or vice versa.

With these and other objects in view, the invention resides in a certain novel construction, combination and arrangement of parts, the essential features of which are hereinafter fully described, are particularly pointed out in the appended claims, and are illustrated in the accompanying drawing, in which:

Figure 1 is a front elevational view of my combination hanger showing the same in use as a coat hanger.

Figure 2 is a front elevation of the combination hanger in use as a hat hanger.

Figure 3 is a side elevational view of the hanger in use as a hat hanger and supported upon the hanger bar on the back of the front seat of an automobile.

Figure 4 is an enlarged detail front elevational view with the cover section of the casing removed, and with parts broken away in section, the operating parts being in the position shown in Figure 1.

Figure 5 is a detail bottom plan view with parts broken away in section.

Figure 6 is a vertical longitudinal sectional view on the line 6—6 of Figure 4, but showing the attaching hook in position for locking engagement with a supporting bar.

Figure 7 is a side elevational view of a modified form.

Figure 8 is a vertical sectional view therethrough, on the line 8—8 of Figure 7.

Figure 9 is a detail sectional view of a further modification.

Figure 10 is a detail vertical sectional view on the line 10—10 of Figure 9.

Referring to the drawing by reference characters, and more particularly to the form of my invention shown in Figures 1 to 6 inclusive, the numeral 10 designates my convertible hanger in its entirety which includes a hollow casing or body 11 of inverted keystone shape in front elevation to provide downwardly diverging side walls 12—12. For the sake of assembling the parts, the casing is constructed of two sections detachably secured together by any desired means. It is preferred to construct the casing of metal so that the same may be stamped and bent into the shape shown.

The top wall of the casing 11 is provided with an elongated slot 12', and slidably mounted within the casing and extending through the slot 12' is an actuating plate 13, the same having spaced parallel elongated slots 14 and 15 provided therein. The slot 12' is of a greater width than the thickness of the plate 13 to permit lateral movement of the plate for a purpose to be presently explained.

Pivoted to the inner end of the plate 13 are the inner ends of a pair of curved resilient supporting arms 16—16, the same being pivoted on opposite sides of the longitudinal axis of the plate 13 as at 17. Both of the inner ends of the arms 16 are pivoted on the same face of the plate 13 and as best seen in Figure 4 of the drawing. The free ends of the arms 16 extend through slots 18 provided in the lower corners of the casing 11 whereby the inner ends of the arms may have free sliding movement through the casing during actuation of the plate 13 in a manner and for the purpose hereinafter explained.

Fixed to the inside of the opposed downwardly diverging side walls 12 are flat springs 19, the free ends of which engage opposite side edges of the plate 13 for the purpose of yieldingly mounting the plate within the casing and for guiding the same during a portion of its sliding movement in opposite directions. A flat spring 20 fixed to the front wall of the casing 11 bears against the plate 13 and tends to press the same toward the rear wall of the casing so as to cause the catch finger 21 bent inwardly from the rear wall to enter either of the slots 14 or 15 when the

plate 13 is actuated to the limit of its sliding movement in opposite directions. The spring 20 permits of the forward movement of the plate 13 to cause the same to disengage the locking finger 21 when it is desired to actuate the plate 13.

An attaching member 22 is pivotally connected to the outer end of the plate 13 as at 23 and the said member comprises a single length of stiff bendable wire bent to provide a shank portion 24 and terminating in a hook 25. Bent from the shank portion 24 is a loop or jaw portion 26 for a purpose to be presently explained.

Pivoted to the bottom of the casing 11 centrally and exteriorly thereof is a catch hook 27 adapted to be swung beyond the rear wall of the casing to secure the attaching member 22 in a clamping position for supporting the hanger during certain uses thereof.

From the foregoing description, it will be seen that by pulling outwardly upon the actuating plate 13 after disengaging the said plate from the catch finger 21, the arms 16—16 are moved from the outwardly spread position shown in Figure 1 to a downwardly extending position where they are in close proximity to each other and constitute clamping jaws. When the plate has been actuated to move the arms in such position, the catch finger 21 automatically enters the slot 15 due to the fact that the spring 20 is constantly pressing the plate 13 in the direction toward the finger 21. When the plate is pulled out to this position, the same converts the hanger into a hat hanger as shown in Figure 2 of the drawing, whereupon the crown A of a hat B may be inserted between the arms 16 which constitute resilient jaws and which serve to clamp the crown without crushing the same. With the hat supported by the hanger, the said hanger may be hung by the hook 25 from a nail, hook or other like support.

When it is desired to convert the hanger into a coat hanger such as shown in Figure 1 of the drawing, the plate 13 is disengaged from the catch finger 21 and is slid inwardly until the catch finger enters the slot 14. During the inward movement of the plate 13, the arms 16 are swung to a raised and outwardly extending position thus forming a support for a coat or like garment. The hanger when in this position may also be supported by the hook 25 from any well known support.

In addition to constituting an accessory for the home, the hanger is adaptable also for use in automobiles when touring, to support a hat or coat in a neat and orderly fashion. Most vehicles are provided with a hanger bar 28 at the rear of the front seat 29 of the vehicle, and which bar is swingingly mounted in bearings 30. It is to such bar that my hanger is adapted to be connected and the same is clearly illustrated in Figure 3 of the drawing. Before attaching the hanger to the bar 28, the same is actuated to form either a coat hanger or a hat hanger, depending upon the nature of the garment to be supported. After adjusting the hanger, the attaching member 22 is swung rearwardly about its pivot 23 so that the jaw or loop portion 26 formed in the shank 24 engages the bar 28 and coats with the casing 11 for clamping the hanger in position. The attaching member is held in clamping position by swinging the catch hook 27 into engagement with the hook portion 25 of the said attaching member. In Figure 3 of the drawing I have shown the hanger adjusted to receive and support a hat upon the hanger bar 28, while in

Figure 6, the attaching member is shown in a clamping position and the parts are in the position which they would assume when the hanger is adjusted to support a coat or other like garment.

In Figures 7 and 8 of the drawing, I have shown a modified form of my invention wherein the numeral 31 designates a casing having a vertical elongated slot 32 in the rear wall thereof, while slidable within the casing is an actuating member in the form of a plate or carrier 33 to which the inner ends of a pair of supporting arms 34 are pivotally connected as at 35. These arms extend through openings 36 in the bottom wall of the casing and rest against the bottom wall when the arms are in an outwardly extended position to form a coat hanger as shown in Figure 8 of the drawing. Passing through the plate 33 and slot 32 is the shank of a threaded bolt 37, while a thumb nut 38 is threaded to the free end of the bolt and is adapted to be screwed tight against the slotted wall of the casing to secure the plate 33 in an adjusted position with the arms in either a coat hanger forming position, or a hat hanger forming position. An attaching member 39 is swivelly connected to the top of the casing 31 as at 39, and which attaching member is substantially identical with the attaching member 22 of the preferred form. A further explanation of this attaching member is not believed necessary.

In Figures 9 and 10 of the drawing, I have illustrated a further modification which is an improvement over the preferred form and like parts are identified by the same reference characters as those applied to the preferred form. In this form of the invention, a coil spring 40 has its opposite ends engaged with pins 41 provided on the inner ends of the arms 16 and which spring tends to pull the arms toward each other during outward sliding of the actuating plate 13. A flat spring 42 fixed to the front wall of the casing 11 bears against the pivoted ends of the arms 16 to position the plate 13 flat against the rear wall of the casing. This spring may be used in conjunction with the spring 20 shown in the preferred form.

From the foregoing description, it will be seen that I have provided a convertible hanger which may be used for supporting either a coat or like garment or a hat, and the same is supported from various types of supports. When the hanger is converted into a hat hanger, the same will be compact for packing and shipping as the attaching member in the form of the hook may be swung down over the body to reduce the length of the article.

While I have shown and described what I consider the most desirable embodiments of my invention, I wish it to be understood that various changes may be resorted to as come within the scope of the appended claims.

Having thus described the invention, what I claim as new and desire to secure by Letters Patent is:—

1. A hanger comprising a casing, an actuating member slidably mounted in said casing, a pair of curved arms having their inner ends pivoted to said actuating member, the free ends of said arms extending outwardly through slots in said casing whereby sliding movement of said actuating member in one direction will cause the said arms to swing to coat hanger forming position and sliding movement of said actuating member in an opposite direction will cause said arms to swing toward each other to a hat hanger forming position, and means for locking said actuating

member against movement after actuation of the same to swing said arms to either position.

2. A hanger comprising a casing, an actuating plate slidably mounted in said casing, and 5 movable beyond one end thereof, a pair of resilient curved arms having their inner ends pivoted to said plate, the free ends of said arms extending through slots provided in said casing, said plate having spaced parallel slots therein, a catch finger 10 extending inwardly from said casing for reception in either of said slots, a spring acting to press said plate against said catch finger, and a supporting hook connected to the outer end of said actuating plate.

15 3. A hanger comprising a casing, an actuating plate slidably mounted in said casing, a pair of resilient curved arms having their inner ends pivoted to said plate, the free ends of said arms extending through slots provided in said casing, 20 said casing having an elongated slot therein, a threaded bolt carried by said actuating plate and passing through said elongated slot, a clamping nut threaded to said bolt and disposed exteriorly of said casing for clamping engagement therewith, and attaching means carried by said casing.

25 4. A hanger comprising a body, supporting arms extending therefrom, a pivoted attaching member adapted to swing to a position behind said body, said member having a jaw portion

30

adapted to coact with the back of said body to clamp the hanger upon a bar support, and a catch member pivoted to the body and engageable with said attaching member to secure the same in a clamping position.

5. A hanger comprising a body, supporting arms extending therefrom, a pivoted attaching member comprising a shank having a jaw portion bent therefrom and terminating in a hook, said attaching member adapted to be swung to a position behind said body to cause the jaw portion to coact with the back of said body to clamp the hanger upon a bar support, the hook portion of said attaching member extending beyond the lower end of said body when swung to clamping position, and a catch hook pivoted to the lower end of said body for engagement with the hook portion of said attaching member when the same is swung to clamping position.

6. A hanger comprising a body, supporting arms extending therefrom, an attaching hook member swingably connected to the top of said body and adapted to be swung to a position adjacent one side of said body and coact therewith to clamp the hanger upon a bar support, and releasable means on said body engageable with said hook member for securing the same in a clamping position.
